UNITED STATES PATENT OFFICE.

JUSTUS J. ROSS, OF HUNTINGTON, WEST VIRGINIA.

METAL MINE TIE.

Application filed March 19, 1924. Serial No. 700,351.

To all whom it may concern:

Be it known that I, JUSTUS J. Ross, a citizen of United States, residing at Huntington, in the county of Cabell and State 5 of West Virginia, have invented certain new and useful Improvements in Metal Mine Ties, of which the following is a full, clear, and exact description.

The invention relates to metal ties which 10 are particularly adapted for motor haulage in mines, and one of the objects of the invention is to provide a tie of this character which is extremely simple in construction and inexpensive in manufacture, and yet 15 which is highly efficient in supporting and securing rails of various weights and sizes.

Another object of the invention is to provide a metallic tie equipped with an extremely simple device which can be instantaneously operated to securely grip rails of various sizes, or rails which are worn or rusted away, and which is so constructed that the gauge will remain the same though 20 rails of different size are employed.

25 A further object of the invention is to provide a tie embodying the above and other features, and in addition thereto is so constructed that it will be securely anchored to the ground, or mine floor, in such manner 30 that longitudinal or lateral movement of the tie will be prevented.

Further objects and advantages of the invention will be apparent from the following detailed description, when taken in connection with the accompanying drawings; 35 in which,

Figure 1 is a longitudinal vertical sectional view of one end of the tie.

Figure 2 is a plan view of the tie; a portion 40 of the rail cap being broken away.

Figure 3 is a longitudinal vertical sectional view of one end of the tie, showing clamped in position a rail of smaller size than that illustrated in Figure 1; and

45 Figure 4 is a longitudinal vertical sectional view of a complete tie.

Referring to the drawings more in detail, 50 numeral 1 indicates the body of the tie which has a flat top surface and downturned side flange 2; that is, the body of the tie in cross-section, has the shape of ordinary channel iron. The flanges 2 strengthen the tie and in addition they function as an anchoring means to prevent lateral movement 55 of the ties. As a further anchoring means, particularly for preventing longitudinal

movement of the tie, I provide short sections of channel steel or iron positioned between the flanges 2 and riveted to the top of the tie; the anchoring channels being indicated by numeral 3. The channels 3 are of sufficient length to extend the full distance between the downturned flanges 2, 2, of the tie so that there is no possibility of 60 the anchoring means becoming displaced from its position as shown in the drawings, for if there should be only one rivet employed, the flanges 2, 2, would prevent the rotation of the anchoring channel 3. It is 65 to be noted that the downturned flanges 4, 4 of the anchoring channel 3 extends below the lower edges of the downturned flanges 2, 2, so it is apparent that all of the flanges will cut into the ground or mine 70 floor and thus prevent movement of the tie in any direction. The anchoring channels are positioned on the tie directly below the rails, so that the weight of the rails will 75 tend to force them in the ground; and further they strengthen those particular portions of the tie which directly support the 80 rails.

Numeral 5 indicates a clamping lug which has a flat portion 6 coinciding with the flat surface of the tie, and an upwardly inclined portion 7 for engaging the flange of the rail or the web of the rail as the case may be, depending on the size of rail employed. The clamping lug is provided with strengthening side flanges 8, and the lug is preferably secured to the tie by means of rivets. The peculiar design of this clamping lug and its novel manner of functioning to secure rails of various sizes without varying 85 the gauge, will now be described.

In Figure 1 is shown in vertical section a relatively large rail clamped in position and a small rail in dotted outline; in Figure 2 is shown a plan view of a relatively large rail in clamped position; and in Figure 3 is shown in vertical section a small rail in clamped position. By reference to these figures, in connection with the following brief description, the design and operation 100 of the clamping lugs will be clearly understood.

The conventional rail consists of the head, web, and flange, indicated respectively by the numerals 9, 10, and 11, for the larger rail; and 9', 10', and 11', for the smaller rail. The clamping lug 5 is so designed that 105 when it is employed in connection with the

largest rails commonly used in mine work, it will follow the contour of the rail flange or base 11, and thus exactly fix the position of the largest rails, as clearly illustrated in Figure 1. It will be noted, however, that the lug does not extend up to the web of the rail when the large rail is employed. Now if the inclined portion 7 of lug 6 was so designed that it was much shorter than illustrated herein, then when a small rail was used, its flange would be forced under the lug until it contacted with the inclined portion at the point where the lug meets the surface of the tie, and consequently there would be considerable variation in the gauge. As clearly illustrated in Figure 3, however, the clamping lug is not so designed, and by an inspection of that Figure it will be seen that when a small rail is employed the web 10' abuts against the free end of the inclined member 7. By this construction the vertical center line of the rail is moved only slightly for different size rails, and this difference in position just about compensates for the difference in the width of the heads of different rails, so that the gauge remains almost exactly the same. I have described the lug in connection with large rails and small rails, and it will be understood that rails of intermediate sizes will assume intermediate positions; the gauge remaining almost identically the same for all sizes of rails.

The cam wedge, indicated generally by numeral 12, which is employed to engage the rail, forces it into engagement with the clamping lug and securely locks the rail in position, will now be described.

The cam wedge 12 is preferably of a general semi-circular shape, and has a flat central portion 13 resting on the flat surface of the tie; the cam wedge being pivotally attached to the tie by means of a loose rivet 14, or by equivalent means. As clearly shown in the drawings, the cam wedge is eccentrically mounted on the rivet 14.

Extending upwardly and outwardly from the flat portion 13 is a gripping flange 15. This flange is shaped to fit the contour of the rail flange, and the peculiar shape of the gripping flange will be apparent from an inspection of Figure 1. The flange, as shown at the left of Figure 1 is of greater length and is spaced farther from the surface of the tie than is the case with the flange shown on the right of Figure 1. The flange on the left of Figure 1 is designed to conform to the contour of the flange of the largest rail to be employed, and the flange on the right of Figure 1 is designed to conform to the contour of the flange of the smallest rail to be employed. The length of the flange 15, and the distance it is spaced from the tie surface, are gradually decreased from the maximum shown on the left of

Figure 1, to the minimum shown on the right of Figure 1; and, of course, intermediate portions of the gripping flange correspond with the contour of intermediate size rails. It will be noted that the gripping flange of the cam wedge is designed to contact with the rail flange and with the rail web, for all sizes of rails, so that it will force the rail into engagement with the clamping lug and hold the rail in a rigid and unyielding manner.

The curvature of the edge of the flat portion 13, that is, the curvature of the edge of the cam which engages the edge of the rail flange, is on a gradually increasing curvature from the left of Figure 1 to the right of Figure 1, to provide for engagement with the edges of rail flanges of various widths; and the curvature of the outer edge of the cam wedge is such that the distance between this edge and the edge of the flat portion of the cam gradually decreases from the left to right of Figure 1 to take care of the more narrow rail flanges of the smaller rails. As previously mentioned herein, the cam wedge is eccentrically mounted on the rivet 14.

From the foregoing description it will be seen that the cam wedge is an inexpensive and highly efficient device for quickly and firmly clamping rails of various sizes; it being only necessary to strike the semi-circular cam with a hammer or other tool to rotate it into clamping position on any size rail. And when this cam wedge is employed in conjunction with the particular clamping lug described herein, it will be apparent that rails of various sizes may be used without varying the gauge.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims:

Having fully described the invention, what I claim as new and desire to secure by Letters Patent is:

1. A metallic cross tie, a fixed clamping lug for engaging one side of the rail flange, a rotatable cam wedge of segmental shape for engaging the other side of the rail flange, said cam wedge provided with a cam edge for engaging the edge of the rail flange of various sizes of rails, and provided with another cam edge for engaging the rail web of various sizes of rails.

2. A metallic cross tie, a clamping lug, said clamping lug adapted to maintain substantially the same gauge with rails of different size, and a cam wedge for forcing the rail into engagement with the clamping lug,

said cam wedge adapted to engage both the rail flange and the rail web of rails of various sizes.

3. A cross tie formed of channel steel, anchoring means provided on the tie, said anchoring means located substantially directly below the rail, a clamping lug, said clamping lug adapted to maintain substan-

tially the same gauge with rails of different size, a cam wedge for engaging the other side of the rail and forcing the rail into engagement with the clamping lug, said cam wedge adapted to conform to the contour of the rail flange of rails of various sizes. 10

JUSTUS J. ROSS.
